[57] ABSTRACT

Apparatus for splicing an old and a new web in abutting relation, comprising a web feed out station, a web cutting station and a web splicing station. The old and new webs are fed from the feed out station into substantially parallel relation and pass between a pair of rotatable drums at the cutting station and a pair of rotatable drums at the splicing station. One of the drums at the cutting station has a blade for cutting the old and new webs, and a perforated old web holding and releasing portion disposed adjacent one side of the blade. The other drum at the cutting station has a perforated new web holding and releasing portion that is disposed on the side of the blade opposite to the one side when the cutting drums are in positions such that the blade is disposed adjacent to the other drum. One of the drums at the splicing station has a perforated portion adapted to retain a splicing tape thereon for application to the abutted new and old webs at the splicing station.

FIG. 3

FIG. 4

FIG. 5

FIG. 6

WEB CUTTING DEVICE IN AN APPARATUS FOR SPLICING AN OLD WEB AND A NEW WEB

BACKGROUND OF THE INVENTION

The present invention relates to an apparatus for splicing webs of paper, plastic, metal foil and the like (hereinafter referred to simply as "web"), and in particular to an apparatus for continuously splicing the web ends when the web is continuously fed into a web treating station.

In the present invention, the webs are spliced by making an end of one of the webs abut against the end of another web and connecting the both ends with each other. A known apparatus for splicing webs in the manner described above is disclosed in U.S. Pat. No. 2,745,464. The splicing apparatus disclosed in the patent is suitable for splicing webs of relatively large thickness as carton paper, but it is not possible to splice webs which are likely to generate static electricity such as plastic web. This is because of the fact that when the overlaid webs are cut at the portion near the ends thereof, the cut piece of one web sticks to the surface of the end of the other web and accordingly the end of the web with the cut piece thereon happens to stick to the surface of the feeding roller and advance under the guide plate on which the end of the web is disposed to abut against the end of the other web. Therefore, the apparatus disclosed in the patent has been disadvantageous in that the splicing of web material likely to generate static electricity is not able to be performed.

SUMMARY OF THE INVENTION

Therefore, an object of the present invention is to provide an apparatus for splicing webs which is able to splice webs that are likely to generate static electricity.

Another object of the present invention is to provide an apparatus for splicing webs which is able to splice effectively webs that are likely to curl.

BRIEF DESCRIPTION OF THE DRAWINGS

Further objects of the present invention will be made apparent from the following description together with the features and advantages thereof taken in conjunction with the accompanying drawings in which:

FIG. 1 is a sectional elevational view of apparatus constructed in accordance with an embodiment of the present invention;

FIG. 2 is an enlarged sectional view of the spliced portion of the webs taken along the longitudinal direction, showing the spliced condition of the webs spliced in accordance with the present apparatus;

FIG. 3 is an enlarged sectional elevational view of the cutting station of the apparatus of the present invention showing the cutting operation thereof;

FIG. 4 is an enlarged sectional elevational view of the cutting station of the apparatus of the present invention, showing the station when the cut webs are fed slightly forwardly;

FIG. 5 is a view similar to FIGS. 3 and 4, showing the station when the cut webs are further fed forwardly with the ends of the webs abutting against each other; and

FIG. 6 is an enlarged sectional elevational view of the splicing station of the apparatus of the present invention.

DESCRIPTION OF THE PREFERRED EMBODIMENT

Now referring to FIG. 1 showing the entire general construction of the apparatus of the invention, the reference numeral 1 indicates a web feed out station having an old web roll 2a and a new web roll 3a rotatably supported in the station. A pass roll 4 for guiding the old web 2 and a pass roll 5 for guiding the new web 3 therealong respectively are provided in the web feed out station at the exit thereof. Downstream of the pass rolls 4 and 5 is disposed a framework 7 supporting a pair of cutting drums 8 and 9 constituting a cutting station of the apparatus and a pair of splicing drums 12 and 13 constituting a splicing station of the apparatus. Between the pair of cutting drums 8 and 9 and the pair of splicing drums 12 and 13 are disposed guide plates 10 and 11. The cutting station is spaced from the splicing station by the distance *l* which is short enough for the cut end of the web to reach the splicing station while the cutting drums are rotated through one revolution that is, the leading end of the cut new web is inserted into the guide plates and reaches the web splicing drums 12 and 13 by the time the web end holding portion 37 comes around back to its original position.

The old web 2 is fed along the pass roll 4 disposed upstream of the framework 7 and along a pass roll 6 disposed downstream of the framework 7 as shown in FIG. 1. One of the pair of the cutting rollers 8, 9 and splicing rollers 12, 13 is urged upwardly by means of a spring or the like. In the present embodiment, the lower rollers 8 and 12 are urged upwardly by springs 35 and 36, respectively. The drums 8 and 12 are provided with hollow rotational shafts 17 and 22, respectively, which are held substantially horizontally in slidable relation with a pair of side guide slots 38 and 39 provided on the framework 7. The slots 38 and 39 have upper limit ends which the shafts 17 and 22 are urged against by the springs 35 and 36. Similarly, the cutting drum 9 and the splicing drum 13 are provided with hollow shafts 41 and 27 respectively.

As best shown in FIG. 3, the cutting drum 8 to be brought into contact with the old web 2 is provided with a cutting blade 14 secured with a bolt 15 thereto. The drum chamber 16 of the cutting drum 8 is connected with a blower (not shown) outside through the hollow portion of the hollow shaft 17. The cutting drum 8 is further provided with a plurality of suction perforations 19 on the drum surface so that the cut piece 2' of the old web may be sucked thereon by pressure reduction within the drum chamber 16. The upper cutting drum 9 is a drum to be brought into contact with the new web 3 and is provided with a partition 42. The cutting drum 9 is further provided with a perforation 24 near the cutting blade receiving portion 20 and a plurality of suction perforations 26 on the surface thereof, the perforations 24 being connected with the chamber 21 and the perforations 26 being connected with the other chamber 25. The chambers 21 and 25 are connected with semi-cylindrical hollow portions 23 and 46, respectively, of the hollow shaft 41. When the perforation 24 is used to suck air therethrough, the cut end of the new web 3 is sucked on the surface of the drum 9, and when it is used to blow air off therethrough, the cut end of the new web 3 is separated from the surface of the drum 9. Similarly, when the air is sucked through

the perforations 26, the cut piece 3' of the new web 3 is sucked on the surface of the drum 9. In order to either blow or suck air through the perforations 24 and 26, the respective compartments 21 and 25 are connected with blowers (not shown). The cutting blade receiving portion 20 and the perforation 24 constitute a web end holding and releasing portion of the cutting drum 9. The plurality of perforations 26 and the substantially flat surface of the drum in the vicinity of the perforations 26 constitute a web cut piece holding and releasing portion of the cutting drum 9.

The upper splicing drum 13 has a drum chamber 31 connected with the hollow shaft 27 and is provided with one or more perforations 30 on the surface thereof so as to suck a splicing tape 29 on the surface thereof when the drum chamber 31 is reduced of its pressure. The hollow shaft 27 has a hollow portion 28 similar to the hollow shaft 17 having the hollow portion 18 in the lower cutting drum 8. The construction of the splicing drum as described above is shown in FIGS. 1 and 6. In the framework 7, there is disposed a suitable power means (not shown) for rotating the drums 8, 9, 12 and 13 in the direction shown by the arrows B, C, D, and E in FIGS. 3, 4 and 6. Referring to FIG. 1, the old or new web 2 or 3 is fed into a web treating station 44 after passing through the web splicing station guided by the pass roll 6. The foregoing spring means 35 and 36 urging the hollow shafts 17 and 22, respectively, upwards, may be in the form of hydraulic pressure cylinders.

In operation, as shown in FIG. 1, prior to the splicing operation the new web 3 is drawn out of the roll in the web feed out station and the end of the new web 3 is sucked by the web holding portion 43 of the cutting drum 9 by suction through the perforations 26 by reducing the pressure within the drum chamber compartment 25 of the drum 9. At the same time, the splicing tape 29 is sucked onto the surface of the splicing drum 13 at the perforations 30 with the adhesive bearing surface facing outwardly. This is also effected by reducing the pressure within the drum chamber 31 of the drum 13.

Thereafter, at the time of feeding the tail end of the old web 2, the end of the old web 2 is detected automatically or manually and the drums 8, 9, 12 and 13 are all rotated in the directions of the arrows B, C, D, and E. When the drums are rotated to the extent as shown in FIG. 3, the new web 3 is overlaid on the old web 2 and cut together by the cutting blade 14 and the blade receiving portion 20. Since the drum chamber 16 of the lower cutting drum 8 is under reduced pressure at this cutting instance, the cut piece 2' of the old web 2 is sucked on the cutting drum 8 at the perforations 19. Further, since the drum chamber 21 is under reduced pressure, the end of the cut new web 3 is sucked on the surface of the cutting drum 9 at the web end holding and releasing portion 37 including the perforation 24, and then released by blowing air through the perforation 24. Before the end of the new web 3 is released from the web holding portion 37, the drums 8 and 9 are rotated to the extent as shown in FIG. 4 with the new web 3 stuck on the drum 9 so that the cut end 3' of the new web 3 may be separated from the cut piece 2' of the old web 2 stuck on the surface of the cutting drum 8, thus overcoming the electrostatic force acting therebetween.

At the instance when the drums are rotated to the extent as shown in FIG. 5, the drum chamber 21 is under increased pressure (the device for reducing or increasing the pressure is not shown in the drawings) so as to blow off the end of the web 3 stuck on the web holding portion 37 of the drum 9. Thus, the end of the new web 3 is moved into the space between the guide plates 10 and 11. In the space between the guide plates 10 and 11, the top end of the new web 3 abuts against the tail end of the old web 2. By the further rotation of the drums, the old and new webs 2 and 3 respectively are fed forwardly in the direction A or A' toward the web splicing station in end-to-end relation. During the above process, the drum chamber 25 of cutting drum 9 is under reduced pressure and, accordingly, the cut piece 3' of the new web 3 is sucked onto the drum surface and is removed. Similarly, the cut piece 2' of the old web 2 is sucked onto the surface of the drum 8 and is removed.

In the splicing station, when the two webs 2 and 3 in the end-to-end relation are fed between the splicing drums 12 and 13 as shown in FIG. 6, the splicing tape 29 is overlaid on the abutting portion of the webs as best shown in FIG. 2. Then the drums 12 and 13 are further rotated in the D and E directions up to the position shown in FIG. 1. Thus, one cycle of the web splicing process is completed.

Though, in the above described embodiment of the apparatus in accordance with the present invention, the cut pieces of the webs and the splicing tape are all held on the surface of the drums by suction, it will be understood that these tapes or cut pieces of the webs may be stuck on the surface of the drums by applying or utilizing adhesive tapes having adhesive layers on the both surfaces thereof. Moreover, the direction of feeding the webs is not limited to the horizontal as disclosed herein, that is, the web may be fed vertically, for example.

As apparently seen from the above description, the end of the cut web fed newly from the web roll is sucked on the surface of the rotating drum while the cut piece 2' of the old web is sucked on the surface of another cutting drum at the position where the both webs are in face contact with each other. Therefore, the webs are prevented from sticking to each other by static electricity. This makes it possible to splice any kind of web, even of thin plastic material, that is likely to generate static electricity.

Further in accordance with the present invention, it will be understood that it is possible for the apparatus of this invention to splice webs of material likely to curl such as paper, metal foil and the like.

I claim:

1. In an apparatus for splicing an old and a new web, comprising a web feed out station, a web cutting station and a web splicing station arranged in order, said web cutting station comprising a pair of rotatable drums between which the old and new webs are advanced, one of said drums being provided with a blade to cut the webs and with an old web holding and releasing portion disposed adjacent one side of said blade, the other of said drums being provided with a new web holding and releasing portion that is disposed on the side of said blade opposite to said one side when the drums are in positions such that the blade is disposed

adjacent to the other drum, the improvement comprising:

upper and lower guide plates extending substantially parallel to the web advancing direction and on opposite sides of the old and new webs respectively and positioned so as to prevent the new web from being attracted to the old web by electrostatic force, said upper and lower guide plates extending between said web cutting station and said web splicing station.

2. The apparatus for splicing webs as defined in claim 1 wherein said other drum in contact with the new web has two compartments, one of which is connected with said web holding and releasing portion and the other of which is connected with a perforation through the surface of said other drum, said perforation being positioned such that it is disposed on said one side of said blade when said drums are in positions such that said blade is disposed adjacent to said other drum, and means for selectively supplying both compartments simultaneously with positive air pressure or suction pressure.

3. Apparatus for splicing webs as defined in claim 1 wherein said web feed out station comprises a web roll support having at least two web roll holding means, one of said holding means supporting the old web and the other of said holding means supporting the new web, and a pair of pass rolls to guide the new and old webs in close parallel relation to each other.

4. In an apparatus for splicing an old and a new web, comprising a web feed out station, a web cutting station and a web splicing station arranged in order, said web cutting station comprising a pair of rotatable drums between which the old and new webs are advanced, one of the said drums being provided with a blade to cut the webs and with an old web holding and releasing portion disposed adjacent one side of said blade, the other of said drums being provided with a new web holding and releasing portion that is disposed on the side of said blade opposite to said one side when the drums are in positions such that said blade is disposed adjacent to the other drum, the improvement comprising:

15 two compartments within said other drum in contact with the new web, one of said compartments being fluid connected to said web holding and releasing portion and including at least one perforation terminating at said new web, the other compartment being fluid connected by at least one perforation through the surface of said drum, with said perforation being positioned such that it is disposed on said one side of said blade when said drums are in position such that the blade is disposed adjacent to said other drum, and
20 means for selectively supplying both compartments simultaneously with positive air pressure or suction pressure.
